METHOD OF FORMING BONDS

Robert Temple, Jr., Brooklyn, N. Y.

Application April 28, 1933, Serial No. 668,371

9 Claims. (Cl. 29—148)

This invention relates to a method of forming bonds by explosively actuated means and relates more specifically to a method of joining male and female members together which consists generally in driving an element into one or both of the members under the impulse created by a confined explosive charge. The invention has an especially important use in forming electrical connections.

Considerable difficulty is experienced in securing, at low cost, a perfect connection between two conductors of electricity, whether the conductors to be joined include two wires, or a wire and a surface, or otherwise. Heretofore the best results have been obtained from welding, brazing, or soldering, it being found that mere pressure between the two portions is insufficient to give a good connection.

One of the electrical connection problems which frequently require welding, with its attendant expense and inconvenience, is in securing bonds to rails. In recent years, however, a hydraulic press has been employed at less expense than welding. A hole is drilled in the rail and a copper bond or terminal which carries the connector wire, is inserted in the hole, the bond having a flange or headed portion at one end to prevent it passing completely through the aperture. The press is then employed to compress the bond within the aperture and a fair result is obtained.

One of the objects of the present invention is the provision of an improved method of forcing a projectile-like member into a solid bond, thereby expanding it to a point where a perfect connection will be obtained.

In its broader aspect, however, the instant invention contemplates the provision of a method of securing a male and female member together by driving a projectile into the male and/or the female member under a high velocity. The projectile may penetrate only the male member thereby expanding its sides against the aperture in the female member, or it may penetrate both members, the perfect connection being obtained as a result of the expansion. In any event, the penetrating action causes the members to expand and by so doing affixes them together under great pressure through the lateral expansion of the materials.

Of the two of many embodiments of the apparatus for carrying out the method which are illustrated in the drawings, one is a device for penetrating rail and other bonds of the kind above referred to, the device including a retractable clamping structure which secures the bond in

place, and explosively actuated means for driving the projectile into the bond, thereby causing the latter to expand and affix it to the rail or other structure with a perfect contact.

The second embodiment illustrated in the drawings is an apparatus for securing a connector to a main cable in tap-off work. In this instance the connector comprises a structure, made preferably of copper and having two or more longitudinal apertures therein, usually parallel with each other. The main cable is cut where it is to be tapped and the two end portions thereof are inserted into one of the apertures wherein they meet substantially midway. A retractable clamping structure is then secured to the connector and a projectile fired thereinto. Thus, the projectile expands the cable and assures a contact of high conductivity. The tap-off wires may then be inserted into the other aperture and a projectile driven thereinto in the same fashion. In the event that the tap-off wire is of smaller diameter than the aperture a copper bushing may be inserted in the aperture. Likewise, if a number of tap-off wires are desired a second connector is employed, having two or more apertures therein.

The invention also contemplates the provision of a method of bonding by explosively actuated means wherein no recoil develops as a result of the firing. This is accomplished by confining and sealing the explosive charge in a manner somewhat similar to that shown in United States Letters Patent Nos. 1,365,869 and 1,365,890 granted to my father, Robert Temple.

A further object of the invention is the provision of a novel method for the securing of a bond terminal to a rail which includes inserting the solid terminal into an aperture in the rail, driving a projectile into the bond with such a velocity as to make the expansion great enough to secure a practically perfect contact, explosively actuated means being employed for the driving power, the result being accomplished without noise, recoil and also without a flame, which would be dangerous in underground work.

With the above indicated objects in view, the invention resides in certain novel constructions and combinations and arrangements of parts, clearly described in the following specification and fully illustrated in the accompanying drawings, which latter show embodiments of the invention as at present preferred.

In the drawings:

Fig. 1 is a front elevation of the first embodiment of the invention, partially in section, the

clamping structure being shown in the safety or non-firing position.

Fig. 2 is a broken vertical section of the embodiment, the detonating portions being shown in firing position.

Fig. 3 is an end elevation of the apparatus.

Fig. 4 is a broken top plan view, partially in section.

Fig. 5 is a section on line 5—5 of Fig. 1, the view showing the pinion removed.

Fig. 6 is a perspective view of the firing pin actuator.

Fig. 7 is a perspective view of the detonator block.

Fig. 8 is a side elevation of the screw which assembles the projectile unit.

Fig. 9 is a broken horizontal transverse section taken through a rail and bond secured therein, the view showing the position of the projectile.

Fig. 10 is similar to Fig. 9 but shows the position of the projectile when fired from the opposite end of the bond.

Fig. 11 shows a modification in the construction of the bond when used for conducting low amperage currents.

Fig. 12 shows the same bond in place.

Fig. 13 is a side elevation, partially in section, of the second embodiment of the invention.

Fig. 14 is a front elevation thereof.

Fig. 15 is a front elevation of the striking tool for the firing pin.

Figs. 16, 17 and 18 are perspective views of reducing bushings employed in the device.

Fig. 19 is a modified connector unit.

Fig. 20 is a broken perspective view of the detonator block.

The first embodiment of the apparatus for carrying out the method is illustrated in Figs. 1 to 8 inclusive, and comprises a substantially U shaped, retractable clamping structure 5. This structure includes a downwardly extending L shaped female member 6 and a downwardly extending male member 7 which carries the explosive means.

The female member 6 is shaped to provide an inwardly extending portion 8 at its lower end to engage the head portion 9 of a conventional solid copper rail bond or terminal 10 which is placed within a newly drilled aperture 11 in a rail 12. These bonds are of standard construction and are secured at each end of a connector wire (not shown).

The annular edges 13 of the face of the portion 8 are preferably bevelled. A centrally disposed aperture 15 extends inwardly from the face.

The horizontal portion 16 of the female member 6 is provided with a longitudinal aperture 17 therein. Within this aperture the horizontal portion 18 of the male member passes, said portion having a plurality of vertically disposed teeth 19 which function as a rack, said teeth being engaged by a pinion 20.

The pinion 20 is mounted for pivoted movement on the horizontal portion 16 of the member 6 in the following manner. A pair of upper and lower lug or pivot supporting portions 22 and 23, respectively, are integral with said horizontal portion 16, said portion having aligned vertical apertures 24 and 25 therein. A shaft 26 having a circular handle 27 is carried within said aperture, said shaft having a flange portion 28 which engages the upper surface of the upper lug 22. Immediately below the flange is a portion 29 of the shaft which fits within the aperture 24 in

the lug. Below this portion is a non-circular portion 30 which carries the pinion 20, as shown in Fig. 4. The lower end 31 of the shaft is circular and of reduced diameter to fit the reduced aperture 25 in the lower lug. The shaft is secured against removal by means of a set screw 33 in the lug, the end of which engages an annular recess 34 in the shaft.

Thus it will be seen that by revolving the handle in one direction the male member 7 moves outwardly to give sufficient clearance at the lower end of the structure to enable it to pass over the head of the rail. By turning it in the opposite direction the members move together to the position shown in Fig. 2. When this position is reached the pinion is secured against rotation by means of a dog 36 pivotally mounted at 37 in lugs 38 and 39, also integral with the horizontal portion 16, the dog being urged outwardly by means of a spring 40, all as clearly illustrated in Figs. 4 and 5.

The male member 7 is secured against rotation within the female member 6 by means of a key 42 secured in a recess in the inner portion of the aperture in the female member, a screw 43 securing said key. The key passes in a longitudinal recess 44 in the male portion 18, all as shown in Figs. 4 and 5.

The following explosive means for driving the projectile into the bond are provided. The vertical portion 46 of the male member 7 is provided, at its lower end, with a circular aperture 47 extending inwardly substantially two thirds of its thickness. Within this aperture a cylindrical sleeve 48 is positioned and is adapted for longitudinal movement. One end of the sleeve is closed and is provided with a threaded aperture 49 in which an externally threaded breeching element 50 is positioned. The breeching element is longer than the thickness of the end portion of the sleeve 48 and an elongated cylindrical barrel 51 is carried on the outer end of said breeching element, the inner end of the barrel being threaded to provide for easy removal. The external diameter of the barrel is of such size as to fit snugly within the sleeve 48, the outer end portion being enlarged as shown at 52, this portion having a polygonal external surface for the application of a wrench. An aperture 53 extends from end to end of the barrel, one end portion having an enlarged portion 54 which fits over the bond 10, and the opposite end also having an enlarged portion 55 which provides an annular shoulder 56 which supports the projectile and explosive element which will now be described.

The projectile, which is designated as 60 is of a tapered construction, and is preferably made from tempered steel, or the like. The opposite end of the projectile is provided with a threaded aperture 61 which carries a threaded screw 62. Inasmuch as no movement of the projectile can take place until the explosive gases have built up sufficient pressure to break the screw, the screw is provided with an annular recess 63 to facilitate the breaking. Adjoining the rear end of the projectile is a cup 64 closely fitting the base of the barrel, said cup having a central threaded aperture through which the screw 62 passes, thereby securing the cup, the projectile and the screw together. A cylindrical detonator block 65, having a threaded aperture 66, is carried at the opposite end of the screw and is of an enlarged diameter to closely fit the enlarged portion 55 of the aperture in the barrel and rests against the shoul-

der 56. A detonator cap 67 is positioned in a recess in the block, said block also having a longitudinal slope 68 through which the flash from the cap may travel into the chamber provided by the cup, which chamber is filled with a suitable charge of powder 69.

Thus, when the detonation takes place, the initial movement of the projectile 60 and the cup 64 is retarded until sufficient pressure is built up to 10 break the screw 62. When this occurs the projectile moves forward and into the bond, the cup being stopped when it strikes the end of the bond. By virtue of the fact that the cup closely fits the bore of the barrel, the explosive gases are not 15 immediately released after the explosion, this fact being responsible for the lack of any recoil in the apparatus.

The following means are employed to actuate the firing pin which is designated as 70, the pin being adapted to pass through an aperture 71 in the breeching element. The pin is integral with a firing rod 72 having a curved headed portion 73 and mounted in an aperture 74. The firing rod is caused to move forward by means of a firing pin 20 actuator 75 illustrated in detail in Fig. 6. The actuator includes an offset portion 76 at the upper end thereof, a spring engaging offset portion 77 substantially midway, and a diagonal portion 78 at the lower end which engages the head 73 of the firing rod 72. The actuator is mounted for longitudinal movement within a slot 80 in the outer surface of the vertical portion 46 of the male member and is secured against removal by means of a plate 81 held thereon by screws 82. 25 The actuator is urged upwards by means of a spring 83 positioned within a recess 84 in the slot 80, the upper end of the spring engaging the offset portion 77.

The actuator is moved downwards by means 30 of a removable pin 85 which is mounted in an aperture 86 in the portion 46, the pin engaging the offset portion 76 of the actuator.

In order to prevent accidental discharge of the apparatus the following safety means are provided. An aperture 88 in the breeching element 50 receives a coil spring 89, the opposite end of the spring engaging the rear wall of the aperture 47 at the lower end of the male member. The spring normally urges the breeching 50 and the 0 sleeve outwardly, as shown in Fig. 1, the outward movement thereof being limited by means of a set screw (not shown). Rotation of the bushing is prevented by means of a key 91, secured at the lower side of the aperture 47 by means of a screw 92, the key extending into a slot 93 in the bushing.

When in this outward position, as shown in Fig. 1, the firing pin 78 does not lie adjacent to the detonating cap 67, thereby preventing accidental discharge. When, however, the handle 27 is revolved further, thereby drawing the male member 7 inwardly to the position indicated in Fig. 2, the firing pin is adjacent to the cap and when the firing rod actuator is moved downwards by the pin 85 the charge is set off and the projectile driven into the bond.

Fig. 9 shows the position of the projectile 60 after it has penetrated the bond 10. The firm support of the bond during the penetration prevents any appreciable amount of the copper from passing out, as shown.

In Fig. 10 the projectile 60' is shown as being fired through the head of the bond which is almost as satisfactory except that some of the cop-

per escapes unless it is very firmly supported at both ends.

Fig. 11 shows a modified form of bond for use in low amperage work wherein a much smaller bond may be used than in high amperage work. 5 This bond is particularly adapted for signal connectors which are secured to the rails.

In this instance an aperture 94 is drilled something less than one-half an inch into the head of the rail 12 and the bond 95 is inserted therein- 10 to. The projectile (not shown) is tapered at a greater angle so that after it is fired it may be readily removed, thus leaving the bond secured with the aperture as shown in Fig. 12.

The second embodiment of the apparatus, il- 15 lustrated in Figs. 13 to 20 inclusive, is an explosively actuated penetrating tool similar to the previous described embodiment. The second embodiment is adapted, however, for use in cases wherein one connector is a male member which is 20 passed into a sleeve or female member, in which case it is desirable to fire a projectile into the combined or assembled members from the side rather than from the end, with the male member only, as in the preferred embodiment. 25 In this second type of work the desired expansion is obtained and a perfect electrical connection results.

In a previous application, Serial No. 557,857 I described a press capable of developing tremen- 30 dous pressure for cable splicing work. In this instance the two ends of the cable to be connected are placed in opposite ends of a copper sleeve which is compressed in a plurality of places under twenty to thirty tons pressure. 35

The second embodiment of the present invention is designed largely for tap-off work rather than cable splicing. It contemplates the use of a copper connector of the type illustrated in Figs. 13 and 14. The connector, which is designated as 100 is preferably cast or pressed from copper and includes two or more integral cylindrical portions 101 and 102 having longitudinal apertures 103 and 104 parallel with each other. For convenience in supporting the connector 40 during the penetrating operation a concave depressed portion 105 is provided on each side. Also to aid in placing the ends of the cable within the apertures the proper distance the central wall 106 is provided in each aperture. 45

When a main cable, which is usually of the size of the apertures 103 and 104, is to be tapped, the cable is cut in the proper position and the ends inserted within one of the apertures and a projectile driven thereinto as hereinafter described. The driving of the projectile causes the cable to expand laterally against the walls of the aperture and give a perfect contact. The other aperture may then be employed to receive the auxiliary tap-off wire. In the event that the latter is smaller than the aperture, reducing bushings 107 and 108 having apertures 109 and 110 of varying sizes may be inserted in the larger aperture and the projectile driven thereinto in the same fashion. 55

Also, in case a number of tap-off wires are required connectors 111 of the type of the type illustrated in Fig. 18 may be employed, said bushing having four longitudinal apertures 115 of the same size. 60

Fig. 19 shows a separate connector unit 112 having a large aperture 116 and four smaller apertures 117, the connector being adapted to be inserted within the apparatus as hereinafter described. 70

The driving device in this instance includes an elongated barrel 120 having an aperture 121 extending therethrough. The lower end of the aperture is slightly tapered as shown at 122 to aid in the removal of the cup portion of the projectile, hereinafter described, after the detonation. The connector 100 rests in a C shaped connector supporting element, 123 having a concave lower portion 124 to receive the connector, and a threaded aperture 125 at its upper end to receive the threaded portion 126 of the barrel. A threaded bushing 127 at the lower end of the barrel is secured against rotation by a set screw 128, the bushing preventing removal of the connector supporting element. When it is desired to insert the connector the barrel is revolved by turning a handle 129 which is keyed to the barrel, and after the connector is in place the handle is revolved in the opposite direction until the lower end of the barrel engages the connector firmly, as shown in Figs. 13 and 14.

Fig. 13 shows the new improvement in the projectile unit which provides means for more effective sealing of the explosive gases in their chamber before the initial movement of the cup and the projectile takes place.

The projectile unit includes a tapered projectile 134 having a threaded aperture 135 at its rear end. A threaded screw 136 is held in this aperture, the screw also supporting the tapered cup 137. The opposite end of the screw is secured to the detonator block 138 similar to that illustrated in the first embodiment, the block having a threaded aperture 139 to receive the screw and a slot 140 to conduct the flash. Thus, the projectile unit is assembled into one piece which separates with sufficient pressure built up to break the screw.

The detonator block in this instance is formed with a reduced portion 141, the shoulder 142 formed thereby engaging the shoulder 143 formed by an enlarged portion 144 at the upper end of the aperture 121 in the barrel.

The reduced portion 141 is hollow forming a circular chamber indicated at 145, the lower edge 146 thereof engaging a shoulder 147 in the barrel, thus giving the detonator block two points of support. The upper edge 148 of the cup 137, when assembled, as shown in Fig. 13, extends into the chamber 145, closely fitting therein to prevent the escape of gases, until sufficient pressure is built up to break the screw.

The detonator block is held in place by means of a screw cap 149 having a central aperture 150 to receive the firing pin 151. The firing pin is secured against removal by a set screw 152 which engages a slot 153 in the firing pin.

In this type of tool it is desired to provide separate and unattached means for striking the firing pin which in this instance is a hammer 154 having a ball head 155.

The hereinbefore described construction admits of considerable modification without departing from the invention; therefore, it is the wish not to be limited to the precise arrangements shown and described, which are as aforesaid, by way of illustration merely. In other words the scope of protection contemplated is to be taken solely from the appended claims, interpreted as broadly as is consistent with the prior art.

What I claim is:

1. The method of securing a substantially solid male member and a female member together which consists in first inserting the male member within the female member, and then driving a

projectile into one of said members at a high velocity under the impulse created by a confined explosive charge, the initial movement of the projectile being retarded until the explosive gases have built up a predetermined maximum pressure. 5

2. The method of securing a substantially solid male member and a female member together which consists in inserting the male member within the female member and then driving a 10 tapered projectile into the male member under the impulse created by a confined explosive charge, the initial movement of the projectile being delayed until the explosive gases have built up a predetermined maximum pressure. 15

3. The method of securing a plurality of substantially solid male members within a female member, which consists in inserting the male members within the female member, and then driving a tapered projectile into the female member 20 under the impulse created by a confined explosive charge, the initial movement of the projectile being delayed until the explosive gases have built up a predetermined maximum pressure. 25

4. The method of securing a substantially solid headed bond terminal to a rail which consists in forming an aperture in the web of the rail of substantially the same diameter as the diameter of the terminal, firmly supporting the terminal in 30 the aperture by means of a releasable clamping structure, driving a tapered projectile into said terminal at a high velocity under the impulse created by a confined explosive charge, the initial movement of the projectile being retarded until 35 the explosive gases have built up a predetermined maximum pressure.

5. The method of securing a substantially solid bond terminal to a rail which consists in forming an aperture in the rail of substantially the same 4 diameter as the diameter of the terminal, driving a projectile into said terminal at a high velocity under the impulse created by an explosive charge, the initial movement of the projectile being delayed until the explosive gases have built up a 4 maximum pressure.

6. The method of securing a substantially solid member to a rail or the like which consists in forming an aperture in the rail of substantially the same diameter as the diameter of the terminal, supporting the member within the aperture, driving a projectile into said member at a high velocity under the impulse created by a confined explosive charge, the initial movement of the projectile being retarded until the explosive gases have built up a maximum pressure, and then removing the projectile from said member. 5

7. The method of securing a substantially solid bond terminal to a rail which consists in forming an aperture in the head of the rail of substantially the same diameter as the diameter of the terminal, supporting the terminal in the aperture, driving a tapered projectile into said terminal at a high velocity under the impulse created by a confined explosive charge, the initial movement of the projectile being retarded until the explosive gases have built up a maximum pressure, and then removing the projectile from said terminal. 10

8. The method of joining the terminals of wires, which consists in inserting said terminals within a coupling having an aperture of substantially the same size as the diameter of the wires, then driving a tapered projectile into said coupling and the wires at a high velocity under the impulse

created by a confined explosive charge, the initial movement of the projectile being delayed until the explosive gases have built up a predetermined maximum pressure.

9. The method of tapping an electrical conductor which consists in severing the conductor at the desired point, then inserting the terminals of the severed conductor within a connector having a plurality of longitudinal bores therein, driving a plurality of tapered projectiles into the con-

5 nector under the impulse created by a confined explosive charge to reconnect said conductor, the initial movement of the projectiles being delayed until the explosive gases have built up a predetermined maximum pressure, then inserting a 5 tap-off conductor within another of said longitudinal bores in the coupling and driving another projectile into said coupling adjacent to said tap-off conductor.

ROBERT TEMPLE, Jr. 10
